UNITED STATES PATENT OFFICE

2,007,105

SELF-WINDING WRIST WATCH

Fritz Barbezat, La Chaux-de-Fonds, Switzerland,
assignor to the firm Bulova Watch Company
Inc., New York, N. Y.

Application August 4, 1933, Serial No. 683,681
In Switzerland July 18, 1933

2 Claims. (Cl. 58—82)

This invention relates to self-winding wrist watches of the type in which the movements of the wrist of the bearer of the watch are used to produce the winding of the driving spring.

5 The object of the invention is to provide a wrist watch of the mentioned type in which the watch movement carrier is rotatably mounted on a frame member to which the strap surrounding the wrist of the bearer is attached, the 10 movement carrier resting however on the wrist of the bearer, so that owing to movements of the hand of the bearer, the muscles of the wrist will move and act on the movement carrier to impart small movements of rotation 15 thereto relative to the frame member, while a suitable mechanism will be provided to transmit these relative movements between the movement carrier and the frame member to the winding spring.

20 Reference will be made to the accompanying drawing showing one form of my invention by way of example.

Figure 1 is a top plan view of a wrist watch embodying the features of my invention.

25 Figure 2 is a side view of the watch.

Figure 3 is a horizontal section on a larger scale showing the winding mechanism seen from the side of the bridges of the movement.

30 Figure 4 is a perspective and diagrammatic view of the winding mechanism.

In the represented embodiment of the invention, the watch movement 1 is enclosed in a case 2 of rectangular shape traversed by a shaft 3 on which is rotatably mounted the movement plate 5 by means of two lateral lugs 4. The shaft 3 is carried by a frame constituted by two longitudinal rods 7 connected together by the cross rods 8 to which the wrist strap 9 is connected. Square ends 6 maintain the shaft 3 against rotation in the members 7.

40 A certain distance above the shaft 3 is disposed a lever 10 mounted on a pivot pin 11 carried by a small bridge 12. One end of the lever 10 forms a fork 13 engaging over a pin 14 carried by the shaft 3. A pawl 15 is rotatably connected to the other end of the lever 10 and coacts with the teeth of a ratchet wheel 16 which is connected in known manner to the main spring barrel of the watch which is not 45 represented. A spring 17 maintains the pawl in engagement with the teeth of the ratchet which is held against return movement by a pawl 18. A spring 19 acts on the lever 10 and tends to maintain it in the position shown in Figs. 50 3 and 4.

When the watch is attached by means of the strap 9 on the wrist of the bearer, the watch case 2 has its bottom resting on the muscles of the wrist. Any movement of the hand of the person causes movements of the muscles of the wrist, and certain of these movements cause a pressure to be exerted from the muscles on the watch case which is forced to turn on the shaft 3 relative to the frame 7, 8, attached to the wrist strap, in the direction of the arrow *f* in Figs. 2 and 4. The bridge 12 and the pin 11 carrying the lever 10 also take part in this movement of rotation, while the pin 14 being carried by the shaft 3 stays relatively fixed and maintains the forked end of the lever 10 fixed. 5 The opposite end of the lever carrying the pawl 15 effects therefore a movement of rotation in the direction of the arrow *f* in Fig. 4 about the pivot pin 11 and the pawl acts on the ratchet 16 and turns it through a small angle 10 in the direction corresponding to the winding of the main spring. When the hand of the person bearing the watch returns to its normal position, the pressure of the muscles of the wrist on the watch case ceases and the case owing 15 to its weight and to the action of the spring 19 tends to move the lever 10 back into its previous position, returns into its normal position 20 on the wrist, while the pawl 15 slides backwards over the teeth of the ratchet 16 during the 25 movement of the case 2 in a direction opposite to that indicated by the arrow *f*.

30 Stop members 20 carried by the watch case and extending above and below one of the frame members 8 limit the movement of rotation of 35 the watch case relative to the frame. Any known safety connection may be introduced into the winding mechanism in order to avoid overwinding of the main spring.

35 It will be understood that I do not limit myself to the precise form and details of construction illustrated herein by way of example only, since these may be varied without departing from the scope of the invention set forth in the appended claims.

40 I claim:

45 1. In a self-winding wrist watch having a spring driven movement, a relatively stationary frame member, a shaft rigidly mounted on said frame member, a movement carrier rotatable about said shaft and adapted to rest on the 50 wrist of the bearer, a wrist strap connected to said frame member for attaching the watch to the wrist of the bearer, an abutment on said shaft, a lever pivotally mounted on the 55

movement carrier and having one end engaged by said abutment, and means for operatively connecting the other end of the lever to the driving spring, whereby upon a movement of 5 the wrist of the bearer, the muscles of the wrist act on said movement carrier to impart a movement of rotation thereto relative to the frame member thereby causing a movement of oscillation of said lever.

10 2. In a self-winding wrist watch having a spring driven movement, a relatively stationary frame member, a relatively movable movement carrier rotatably mounted on said relatively stationary frame member and resting on the wrist

of the bearer, a wrist strap having its two ends connected to the frame member for attaching the watch to the wrist of the bearer, a lever pivotally mounted on said movement carrier, means for operatively connecting said lever to the driving spring, and means on said stationary member engaging one end of said lever, whereby upon a movement of the wrist of the bearer, the muscles of the wrist act on said relatively movable movement carrier to impart 10 a movement of rotation thereto relative to said relatively stationary frame member so as to cause a movement of oscillation of said lever.

FRITZ BARBEZAT.
